US0D1061113S

(12) **United States Design Patent** (10) Patent No.: **US D1,061,113 S**
(45) Date of Patent: ** Feb. 11, 2025

(54) **KETTLE**

(71) Applicant: **Hy Cite Enterprises, LLC**, Middleton, WI (US)

(72) Inventors: **Craig Stevenson**, Fitchburg, WI (US); **Aric Dichraff**, McFarland, WI (US); **Chor Leung Ko**, Warrington (GB); **Chi Wai Chan**, Hong Kong (CN); **Shang Xin Yan**, Guangdong (CN); **Morad Ghassanian**, Oak Park, IL (US); **Julio A. Salva Alvarez**, Madison, WI (US); **Guan Xun Ou**, Dongsheng (CN)

(73) Assignee: **Hy Cite Enterprises, LLC**, Middleton, WI (US)

(**) Term: **15 Years**

(21) Appl. No.: **29/830,628**

(22) Filed: **Mar. 14, 2022**

(51) LOC (15) Cl. **07-01**

(52) U.S. Cl. **D7/312**

(58) **Field of Classification Search**

(57) **CLAIM**

The ornamental design for a kettle, as shown and described.

DESCRIPTION

FIG. 1 is a perspective view of a kettle showing the new design;

FIG. 2 is an elevation view of a first side of the kettle shown in FIG. 1;

FIG. 3 is an elevation view of a second side of the kettle shown in FIG. 1;

FIG. 4 is an elevation view of a first end of the kettle shown in FIG. 1;

FIG. 5 is an elevation view of a second end of the kettle shown in FIG. 1;

FIG. 6 is a top view of the kettle shown in FIG. 1; and, FIG. 7 is a bottom view of the kettle shown in FIG. 1.

The broken lines shown in the drawings illustrate portions of the kettle and form no part of the claimed design.

1 Claim, 7 Drawing Sheets
